Primary Examiner—Alan P. Douglas*Assistant Examiner*—Cynthia M. Chin(74) *Attorney, Agent, or Firm*—Wm. Brook Lafferty(57) **CLAIM**

The ornamental design for a ground wire connection portion, as shown and described.

DESCRIPTION

FIG. 1 is a perspective view of a new connection shroud portion according to the present invention;

FIG. 2 is a front view of the design shown in FIG. 1;
FIG. 3 is a left side view of the design shown in FIG. 1;
FIG. 4 is a right side view of the design shown in FIG. 1;
FIG. 5 is a top view of the design shown in FIG. 1; and,
FIG. 6 is a bottom view of the design shown in FIG. 1.
The broken lines in the drawings are for illustrative purposes only and form no part of the claimed design.
